UNITED STATES PATENT OFFICE

2,620,931

STEEL BAR CONVEYING APPARATUS

Love Winston, Chicago, Ill.

Application October 3, 1950, Serial No. 188,105

17 Claims. (Cl. 214—1)

1

My invention relates to conveyors usable for moving steel bars outside of steel plants to loading zones, and is an improvement over the structure patented by me on August 13, 1946, under Patent No. 2,405,920. One object of the improved conveyor is to provide better facilities for handling and moving the steel bars.

A further object is to group or pile the steel bars together for better loading efficiency.

Another object is to provide means for handling different types of bars.

A still further object is to provide handy and efficient controls.

With the above objects in view, and any others which may suggest themselves from the description to follow, a better understanding of the invention may be had by reference to the accompanying drawings, in which—

Fig. 1 is a top plan view of the apparatus;

Fig. 2 is a side elevation thereof;

Fig. 3 is an enlarged fragment of the right-hand portion of Fig. 1;

Fig. 4 is a section on the line 4—4 of Fig. 3, showing the conveyor in the initial position;

Fig. 5 is a view similar to Fig. 4, showing a step in the progress of the conveyor;

Fig. 6 is a view similar to Fig. 5, showing a further or final step in the progress of the conveyor;

Fig. 7 is a perspective view of the frontal portion of the apparatus;

Fig. 8 is a section of a detail, taken on the line 8—8 of Fig. 1;

Fig. 9 is a top plan view of the apparatus with the upper units removed to reveal the lower portion of the apparatus;

Figs. 10 and 11 are, respectively, sections on the lines 10—10 and 11—11 of Fig. 9; and

Fig. 12 is a section on the line 12—12 of Fig. 3.

In accordance with the foregoing, specific reference to the drawings indicates the base of the structure at 15, the sides of the same being built up with the rails 16 comprising the track of the conveyor. The base is divided along the center to define a space in which a channeled track 17 is located, such track running well to the rear of the base.

The base 15 is formed with a transverse support 19 at its rear end, which has bearings 20 for a pair of rollers 21, these being designed to receive each bar 22 of steel as it comes from the plant, in a manner similar to the receiving rollers of my patented structure; and an end stop 23 is provided for the bar 22.

As in the previous case, a carriage 25 is provided to bear the weight of each bar as it is car-

2

ried forward, the lateral sections 26 of the carriage being similar to those in my patent. Thus, the rear ends of the track rails 16 are curved down with approaches 27; and the conveyor sections have rollers 28 to facilitate the climbing and travel of the carriage sections over the track rails.

The forward travel of the steel bar is initiated by a pusher carried by a motor belt drive. Thus, a motor 29 operates the main shaft 30 of the drive, which is at the forward end of the conveyor and carries a pulley 31. The center channel 17 is extended rearwardly with a journal 32 for a pulley 34 in line with the pulley 31. A belt 35 connects the two pulleys and is mounted on the pulley 31 in winding relation, so that the drive will be positive in either direction.

The carriage 25 receives a center glider 40 mounted on wheels 41a to run in the channel 17 and having upright end pieces 41 connected by a longitudinal track strip 43. A slide 45 is designed to operate forth and back along the track strip, and is formed in the manner of a receptacle through whose ends the upper run of the belt 35 extends. The pusher 50 for the steel bar 22 is mounted over the slide 45. Thus, the forward portion of the pusher receives the rear end of a link 51 whose forward end is journaled in a bearing 52 of the slide; and the rear end of the pusher dips into the slide and is tied at 53 to the upper run of the conveyor belt 35. Normally, that is, when the slide 45 is behind a steel bar laid over the rollers 21, as shown in Fig. 4, the pusher 50 is in a collapsed position over the slide. However, when the upper run of the belt moves forwardly, its pull on the rear end of the pusher causes it to break upwardly with the link 51, so that the pusher is raised until its rear end meets a forward abutment 55 of the slide and assumes a substantially vertical position behind the steel bar, as shown in Fig. 5. Now, the continued action of the conveyor belt 35 causes the pusher to impinge forwardly on the bar and transfer it from the rollers 21 upon the side sections 26 of the conveyor carriage 25. The fact that the pusher 50 bears on one end portion of the bar 22 will not cause it to advance unevenly, as two or more units of the present apparatus are designed to be located abreast to support the balance of the bar 22, the pushers of all the units acting simultaneously.

The carriage 25 has a pair of laterally spaced strips 60 which primarily form abutments for the front edge of the bar; and the forward travel of the latter is therefore transmitted to the carriage by way of the strips 60, so that the bar may

continue its travel properly supported by the side sections 26 of the carriage.

The glider 40 has an associated slide 65 which terminates at its forward end with a cross-head 66 presenting upward terminal bends 67. At a certain point in the forward travel of the carriage, the bends 67 meet a pair of stops 68 which cause the slide 65 to recede and operate through a certain linkage to lower the abutment strips 69 which are situated in front of the steel bar. Now, the continued forward urge of the pusher 50 will move the steel bar downwardly over the inclined forward ends 69 of the carriage sections 26, so that the steel bar will fall on the track rails 16. The fall of the bar will be broken by a rocker frame 70 fulcrumed in bearings 71 extended from the slide 65, the rear portion of the rocker frame being weighted as indicated at 72. Thus, while the rocker frame is normally in poised position, as indicated in Fig. 4, it yields to the fall of the steel bar as the latter is pushed off the carriage. The belt drive now may be reversed to return the pusher to the original position, where it will be in readiness to negotiate the next steel bar and repeat the operation. However, with the first bar in place, the dropping action of the second bar would have to occur a commensurate distance back if the second bar is to be deposited next behind the first bar. For this purpose, the rocker frame 70 is utilized as a measure when it meets the first bar as the second one approaches the depositing zone to stop the carrier and cause the pusher to deposit the second bar on the rocker frame and on the track rails 16 as the rocker frame yields, as was done in the case of the first bar. Therefore, a number of bars may be deposited in succession over the track by repeating the above process, so that the crane or other loading unit will have a sufficient number to pick up at each operation.

The stops 68 are also usable as against the steel bars themselves. In other words, after a steel bar has been carried forward, the stops may be found in an upright position to limit the travel of the steel bar to their location. Then, the cross-head 66 of the slide 65 will itself meet a cross-bar 75 forming part of a slide 76 which is positioned to travel in the center channel 17. The cross-bar 75 is extended terminally with side brackets 73 which are perforated with slots 79 for the passage of the stops 68. The latter are carried by sleeves 80 of rectangular cross-section and operable along bars 82 of angle section, these being journaled endwise in brackets 83 carried by the track rails 16, as shown more clearly in Fig. 8. Thus, the stops 68 may be swung from horizontal, inwardly directed positions to the upstanding positions indicated in Figs. 1 and 6 through the clearances afforded by the slots 79. Now, when the cross-head 66 meets the cross-bar 75, the action previously described is repeated in respect to the steel bar 22, and the latter is deposited next behind the stops 68.

The stops 68 are designed with a tendency to maintain their upstanding positions. This is done by forming the bars 82 with cross-arms 93 at their front ends, the outer sections of the cross-arms carrying weights 91. The base 15 is designed to be supported by piers 93 or other suitable means some distance above the ground, so that room is had underneath the base for journaling a crankshaft 95 in brackets 96 depending from the track rails 16. The crankshaft has forward throws 97 from which links 98 extend to the inner sections of the arms 90. The

crankshaft 95 is extended rearwardly with a radius arm 99 on the outside of the track. Here, the end of the radius arm is linked to a long rod 100 which extends rearwardly through a bearing 102 carried by the correspondingly positioned rail 16 to terminate with an outward bend 104 in the form of a handle. Fig. 7 shows the mechanism just described corresponding to the normal or upward positions of the stops 68. However, when the handle 104 is pushed forwardly, the crankshaft 95 is rotated to pull down on the inner sections of the cross-arms 90, rotating the bars 82 in directions to swing the stops 68 toward each other and down. At such time, the handle 104 of the rod 100 has tensioned a spring guide 110 carried by the associated track rail 16 and tripped a downward offset 111 formed near the forward end of the guide, stopping the rod 100 from receding and maintaining the stops 68 in the lowered positions. The guide 110 carries a finger piece 115 at its forward end which may be depressed to release the rod 100 from the stopping effect of the guide. In such event, the weights 91 will act automatically to swing the arms 90 of the bars 82 and return the stops to the upstanding positions.

It is intended that the stops 68 be adjustable forwardly or rearwardly to assume desired positions, and means are therefore provided to make this possible. Such means involve a pair of pulleys 120 and 121 journaled in the base 15 and located in longitudinally spaced relation alongside the channel 17. A belt 123 is mounted on the pulleys and attached in wound relation to one of them, so that the action of the belt is positive when such pulley is operated; and a side wing 125 of the slide 76 is attached to the upper run of the belt 123 as indicated at 126. Also, the shaft 128 of the pulley 121 extends to one side of the track with an operating crank handle 130. Thus, the operation of the latter in one or the other direction will carry the slide 76 accordingly and position the stops 68 at the desired point. When this has been attained, a detent 132 operating from a bracket 133 carried by the related track rail 16 may be projected into the periphery of a ratchet wheel 135 carried by the pulley shaft 128, so as to stop the pulley from rotation and the stops 68 from rearward motion.

It is desirable that a control be had for the motion of the carriage 25 in an emergency to stop the same. A brake is therefore provided in relation to the cross-head 66, a cross-slide 140 being mounted on the same which projects a shoe 141 outside the channel 17. The brake is in the form of an angle bar 143 which is parallel to the channel and designed to move toward the same and engage the shoe 141. The action of the brake is initiated by pressure on a lever 150 positioned alongside one of the track rails. The lever is carried by a shaft which is rotatable in a bearing 151 attached to the rail. The end of the shaft opposite from the lever is formed as a crank 154 which is opposite the upper end of a bend 155 made upwardly from a cross-bar 156 which is slidable in bearings 157 projecting downwardly from the base 15. The cross-bar 156 is located near the rear end of the conveyor; and a similar but shorter cross-bar 160 is located near the front end thereof. The two cross-bars 156 and 160 are connected for joint transverse motion by being formed with bends 162 and 163 which are attached to cranks 164 made terminally from a longitudinal shaft 165 carried in bearings 166 attached on the outside of the remotely

located rail 16. Thus, down pressure on the lever 150 operates to slide the cross-bars 156 and 160 inwardly; and they are attached to the angle bar 143 by bolts 168, so that such angle bar is thus applicable as a brake to the shoe 141 at any point in its travel.

The linkage operative to lower the abutment strip 60 will now be described. The abutment strips are vertically slidable in guides 170 carried by the carriage sections 26; and the guides are extended with horizontal brackets 171 formed with laterally spaced bearings 172 for the rockable disposal of members 175. The forward end of each one of these is weighted, as indicated at 176, while the rear end 177 projects to a point under the related abutment strip 60. Thus, the weights 176 operate to normally maintain the abutment strips in an elevated position.

The slide 65 extends with rearward branches 180 at points underneath the carriage sections 26; and the branches are formed with outward pins 181 connecting with stirrups 183 whose upper ends are pivotally suspended at 184 from the carriage sections. Each stirrup is extended with a forward arm 185 in the direction of the related abutment strip 60; and the latter has a rearward lug 187 positioned beneath the said arm. Thus, when the slide 65 meets a stop on the forward travel of the carriage, the recession of the slide causes the stirrups 183 to rock, with the arms 185 depressing the lugs 187 of the abutment strips 60, whereby to lower the same.

Since the abutment strips are made sufficiently broad to form suitable edge supports for the steel bar 22, it follows that a considerable amount of friction may occur when the abutment strips are lowered as just described. In order to relieve them of the larger amount of friction, reference to Fig. 12 shows that a pair of vertical wire rods 190 is disposed behind them, so that the frictional contact by the steel bar 22 will be only with the wire rods 190 and therefore comparatively slight. Each wire rod is formed with a side bend 191 and a bottom cross-shank 192 which is journaled in bearings 193 extended from the carriage sections 26; and said cross-shank is extended outwardly from the bearings to terminate with a pendent portion 194 which is weighted at 195, so that the wire rod 190 may be kept in vertical position normally. Being rockable, the wire rod structure will follow the abutment strips when the pressure to unload the steel bar occurs, simply folding over the top of the abutment strips; and such structure will immediately return with the wire rods in vertical position when the steel bar has passed, to be in back of the abutment strips again when these rise on the return of the carriage.

According to the structure so far described, the steel bars are moved forwardly in the flat position originally laid—as shown in Fig. 4—and unloaded in succession on the track rails. However, it is desirable at times to set the steel bars on edge in the successive order; and a simple attachment is provided which makes this possible. Thus, the brackets 171 are formed with upward stems 200; and Fig. 12 shows one of a pair of guides 202 forming the attachment and mounted on the stem. Each guide has a horizontal portion 203 formed with a rear downbent sleeve 204 which is slidable over the related stem 200. The forward portion of the guide 202 comprises a downbend 205 extended laterally with the guide 202. Thus, on the forward travel of the steel bar, it is pushed onto the guides 202 and forward-

ly therefrom with the effect of sliding in tilted fashion over the bent portions 205 thereof. Now, a dog 208 pivoted inside the pusher, as indicated at 209, is in a forwardly projected position, as shown in Fig. 5 by means of finely dotted lines, so that the continued advance of the pusher acts through the dog to raise the tilted bar to upright position, whereby to rest with its bottom edge on the track rails. Needless to say, the process may be repeated as each unloaded bar forms an abutment for the poised rocker frame 70; the receiving action of the slide 65 occurring in such event.

It will now be apparent that the improved machine has a number of novel features. First, the pusher for the steel bars is a simple accessory for the belt drive, rising to accomplish its function on the forward drive, and automatically collapsing on the return to clear the next bar which may have been deposited on the rollers 21 as the first bar was unloaded. Further, the rocker frame 70 is an independent unit which is always ready to find an unloading bar as a stop or limit to control the progress of the slide 65 with relation to the deposit of the next bar. Further, the abutment strips 60 form primary stops for the steel bar as it mounts the carriage, so that the advance of the same will occur from the pusher through the deposited steel bar. Further, the destination stops 68 are normally held in upright position by the weights 91, yet such stops may be readily adjusted to desired positions along the course of steel bar travel and locked in such positions; and a simple mechanism permits the destination stops to be folded inwardly in case they are not needed for a given operation. Further, means are provided for facilitating the easy operation of the mechanism despite the load imposed by the steel bars; and attachments are provided for assembling the steel bars in lateral edgewise contact and with edges at the bottom as assembled in forward direction, while other attachments facilitate the assembling and nesting of angle and S-section bars. Consequently, the novel machine is not only a labor-saving device, but handles a variety of work without material alteration.

While I have described the invention along specific lines, various minor changes or refinements may be made therein without departing from its principle, and I reserve the right to employ all such changes and refinements as may come within the scope and spirit of the appended claims.

I claim:

1. A conveying apparatus for steel bars and the like, comprising supports on which the bar is deposited, a carriage upon which the bar is advanced from the supports, a track over which the carriage travels in forward direction, and means for engaging the bar when on the supports to induce its forward movement onto the carriage, such means comprising a second track, parallel to the first, a belt drive operating with runs over and under the second track, and a pusher connected to the upper belt run and effective on the advance of the latter to engage the bar for the forward movement, and second means independent of said bar to elevate the pusher for said engagement during forward travel and collapse the pusher during rearward travel.

2. A conveying apparatus for steel bars and the like, comprising supports on which the bar is deposited, a carriage upon which the bar is advanced from the supports, a track over which

the carriage travels in forward direction, and means for engaging the bar when on the supports to induce its forward movement onto the carriage, such means comprising a second track parallel to the first, a belt drive operating with runs over and under the second track, and a pusher connected to the upper belt run and effective on the advance of the latter to engage the bar for the forward movement, a second support disposed in the second track, a slide operable along the second support longitudinally of said upper run and limited in one and the other direction by the connection between the pusher and said upper run, and an element carried by the slide and forming break-links with the pusher, such break-links closing on the forward motion of said upper run to engage the pusher with the slide for the forward propulsion thereof, and the break-links opening on the rearward motion of said upper run to collapse the pusher upon the slide and move the latter rearwardly on the return travel of the pusher.

3. A conveying apparatus for steel bars and the like, comprising supports on which the bar is deposited, a carriage upon which the bar is advanced from the supports, a track over which the carriage travels in forward direction, and means for engaging the bar when on the supports to induce its forward movement onto the carriage, such means comprising a second track parallel to the first, a belt drive operating with runs over and under the second track, and a pusher connected to the upper belt run and effective on the advance of the latter to engage the bar for the forward movement, a glider operable on the second track, and a slide operable forth and back along the glider and carrying said pusher, the glider having end limits engageable by the slide with the effect of propelling the glider in either direction when the slide approaches the corresponding end limits of its travel.

4. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, and means between the slide and said abutments to lower them when the slide meets said stop means on the forward travel of the carriage.

5. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, said abutments being broad and

adapted to support the bar on its forward movement to leave the carriage, and second means behind the abutments of a relatively narrow dimension and designed to relieve them of friction along said edge when the abutments descend.

6. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, said abutments being broad and adapted to support the bar on its forward movement to leave the carriage, and second means behind the abutments of a relatively narrow dimension and designed to relieve them of friction along said edge when the abutments descend, said second means comprising wire rods which are foldable by the influence of the bar upon said abutments on the descent of the same.

7. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, said abutments being broad and adapted to support the bar on its forward movement to leave the carriage, and second means behind the abutments of a relatively narrow dimension and designed to relieve them of friction along said edge when the abutments descend, said second means comprising wire rods pivotally mounted in the carriage to fold by the influence of the bar upon said abutments on the descent of the same.

8. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, said abutments being broad and adapted to support the bar on its forward movement to leave the carriage, second means behind the

abutments of a relatively narrow dimension and designed to relieve them of friction along said edge when the abutments descend, said second means comprising wire rods pivotally mounted in the carriage to fold by the influence of the bar upon said abutments on the descent of the same, and said wire rods being counter-weighted to be restored to the original position when the bar has cleared the abutments.

9. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, the forward progress of the bar from the abutments leading to the deposit of the bar upon the first track, and an intermediate temporary support for the bar effective prior to such deposit and carried by the second slide.

10. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, the forward progress of the bar from the abutments leading to the deposit of the bar upon the first track, and an intermediate temporary support for the bar effective prior to such deposit and carried by the second slide, such temporary support comprising a rocker frame with its forward portion poised in the depositing path of the bar, the rear portion of the rocker frame being counter-weighted.

11. A conveying apparatus for steel bars and the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, and other means to return the abutments to their original positions on the backing of the slide from said stop means.

12. A conveying apparatus for steel bars and

the like comprising a track extending from a rear to a forward location, a carriage adapted to receive the bars in positions transversely of the track and travel forwardly on the same, a second track parallel to the first, a glider operable on the second track and having means for loading the bars on said carriage on the forward movement of the glider, a slide mounted on the carriage and movable relative to said glider, abutments for the forward edge of the bar carried by the carriage and movable downwardly to clear said edge, stop means for the slide associated with the first track, means between the slide and said abutments to lower them when the slide meets said stop means on the forward travel of the carriage, and said abutments having supports pivoted to the carriage, such supports being counter-weighted to return the abutments to their original positions on the backing of the slide from said stop means.

13. A conveying apparatus for steel bars and the like, comprising supports on which the bar is deposited, a carriage upon which the bar is advanced from the supports, a track over which the carriage travels in forward direction, and stop means for the carriage mounted alongside the track, such stop means being adjustable along the latter, said stop means including guide bars parallel to the track and journaled endwise in the same, sleeves slidable along the guide bars, and pins normally projected upwardly from the sleeves to be in the path of said carriage, the rotation of the guide bars folding said pins inwardly to clear the carriage.

14. A conveying apparatus for steel bars and the like, comprising supports on which the bar is deposited, a carriage upon which the bar is advanced from the supports, a track over which the carriage travels in forward direction, and stop means for the carriage mounted alongside the track, such stop means being adjustable along the latter, said stop means including guide bars parallel to the track and journaled endwise in the same, sleeves slidable along the guide bars, pins normally projected upwardly from the sleeves to be in the path of said carriage, the rotation of the guide bars folding said pins inwardly to clear the carriage, and means to restore the pins to their original positions, such means comprising counter-weights effective to rotate the guide bars in reverse direction.

15. A conveying apparatus for steel bars and the like, comprising supports on which the bar is deposited, a carriage upon which the bar is advanced from the supports, a track over which the carriage travels in forward direction, and stop means for the carriage mounted alongside the track, such stop means being adjustable along the latter, said stop means including guide bars parallel to the track and journaled endwise in the same, sleeves slidable along the guide bars, pins normally projected upwardly from the sleeves to be in the path of said carriage, and manually controlled means to rotate the guide bars, the rotation of the latter folding said pins inwardly to clear the carriage.

16. A conveying apparatus for steel bars and the like, comprising supports on which the bar is deposited, a carriage upon which the bar is advanced from the supports, a track over which the carriage travels in forward direction, and stop means for the carriage mounted alongside the track, such stop means being adjustable along the latter, said stop means including guide bars parallel to the track and journaled endwise in

75

the same, sleeves slidable along the guide bars, pins normally projected upwardly from the sleeves to be in the path of said carriage, manually controlled means to rotate the guide bars, the rotation of such guide bars folding said pins inwardly to clear the carriage, a slide operable in the second track, brackets extended from the slide to receive said pins, and manual means to operate such slide with the effect of moving said pins and sleeves along said guide bars.

17. A conveying apparatus for steel bars and the like, comprising supports on which the bar is deposited, a carriage upon which the bar is advanced from the supports, a track over which the carriage travels in forward direction, and stop means for the carriage mounted alongside the track, such stop means being adjustable along the latter, said stop means including guide bars parallel to the track and journaled endwise in the same, sleeves slidable along the guide bars, pins normally projected upwardly from the

10 sleeves to be in the path of said carriage, manually controlled means to rotate the guide bars, the rotation of such guide bars folding said pins inwardly to clear the carriage, a slide operable in the second track, brackets extended from the slide to receive said pins, and manual means to operate such slide with the effect of moving said pins and sleeves along said guide bars, such brackets having clearances for the folding and unfolding travel of such pins.
